UNITED STATES PATENT OFFICE.

CHARLES MITCHELL, OF POUGHKEEPSIE, NEW YORK, ASSIGNOR TO WILL-COX & GIBBS SEWING MACHINE COMPANY, OF NEW YORK, N. Y., A CORPORATION OF NEW YORK.

SEWING-MACHINE TABLE.

No. 845,471.

Specification of Letters Patent.

Patented Feb. 26, 1907.

Application filed July 27, 1906. Serial No. 328,063.

To all whom it may concern:

Be it known that I, CHARLES MITCHELL, a citizen of the United States, and a resident of Poughkeepsie, Dutchess county, and State of New York, have invented certain new and useful Improvements in Sewing-Machine Tables, of which the following is a specification.

My invention relates to the construction of tables for manufacturing purposes, and more particularly work-tables for sewing-machines for use in factories; and the main object of my invention is to construct such a table so that the supports or frames will be adaptable for various positions of the counter-shaft and various styles or arrangements of table-tops and so that the supports may be conveniently shipped without packing and yet without danger of breakage.

In the accompanying drawings, Figure 1 is an end elevation of a single table. Fig. 2 is a similar view of a double table. Fig. 3 is a section on the line 3 3, Fig. 2. Fig. 4 is an end view of a modified form of double table; and Fig. 5 is a perspective view of the same, illustration of the bolts and nuts being omitted for the sake of simplicity.

The table legs or frames of sewing-machine or other work-tables for factory use have usually been made of cast-iron, and these have to be carefully packed for transportation to prevent breakage. They also allow of little or no variation in the positions of the bearings for the counter-shaft. I build my supporting-frames of rolled or otherwise wrought flanged bars, principally channel-bars, of iron or steel, so that they need little or no packing for transportation and they allow a wide range of location and adjustment for the shaft-bearings, and similar parts may be made up to constitute frames for various types or styles of tables. In each case each supporting-frame is made up of two uprights A A', a top cross-piece B', (B² or B³), and a lower cross-piece B. Each of these uprights and cross-pieces is composed of two channel-bars or angle-bars, as a a or b b, arranged back to back and riveted or bolted together, but with a space between the two channel-bars. I prefer to use channel-bars for the uprights and lower cross-piece and angle-irons for the upper cross-piece. The cross-piece B is united to the uprights by

corner-webs 7 7, which may be riveted to the cross-piece and may be secured to the uprights by bolts and nuts 8, a series of openings (holes or slots) being formed in the uprights to enable the cross-piece to be secured at any desired height. In the different views of the drawings I have shown this lower cross-piece as secured at three different heights. The upper cross-piece will vary somewhat in size and shape with the varying style of table-top used. Thus in Fig. 1 I have shown a single table with a flat top H, and the cross-piece is a short straight piece B', composed of two angle-irons, which may be riveted together and to intermediate corner-webs 9, by which the top may be bolted to the uprights by bolts 70 and nuts 10.

In the case of the double table shown in Fig. 2 the upper cross-piece B² is longer and extends considerably beyond the uprights, to which it is united by double corner-webs 11. In the case of the double table with intermediate trough T the angle-irons of which the upper cross-piece B³ is composed are bent to accommodate the trough, as shown in Figs. 4 and 5. In addition to the double corner-webs 12 there may be inserted strengthening-webs 13 at the angles of the trough, Fig. 4. In each of these constructions it will be preferable to provide slots in the webs 9, 11, and 12 for the passage of the securing-bolts, as indicated by dotted lines in Fig. 4, to give a suitable range of adjustment as well as convenience in assembling. In the case of the single sewing-machine table, Fig. 1, I hinge to the back at x a delivery-apron D, and to the apron I pivot one or more braces d, with holes or slots to receive securing-bolts 14, passing through holes in the rear uprights, and so to hold the apron at any suitable adjusted angle convenient for the delivery of the goods from the sewing-machines.

One of the principal advantages of my improved construction of table-frame is that it adapts itself to varying positions of the counter shaft, and in connection with the frame I have adopted a special form of hanger for the bearing of the shaft—that is to say, I provide the hanger E (E') of whatever form with a slotted web e (e'), which may be inserted at any suitable point between the channel-irons of either the cross-beam B or

the upright, as shown in Fig. 1, and there secured by bolts 15 passing through slots in the beam or upright and held by suitable nuts.

5 Fenders F, carried by brackets bolted to the uprights, may be provided.

In the following claims I use the term "flanged bar" in a sufficiently general sense to include either channel-iron or angle-iron.

10 I claim as my invention—

1. The herein-described work-table, comprising a table-top and supporting-frames, each consisting of flanged upright bars in pairs and two cross-pieces, both formed of 15 pairs of flanged bars with corner-webs between the pairs of bars and uniting the uprights to the cross-pieces.

2. The herein-described work-table, comprising a table-top and supporting-frames, 20 each made of pairs of flanged bars secured

back to back but spaced with hangers for shaft-bearings having webs adapted to be secured between adjacent bars.

3. The herein-described work-table, comprising a table-top and supporting-frames, 25 each consisting of uprights and cross-pieces, both made of pairs of flanged bars secured back to back but spaced, with connecting-webs at the corners and with hangers having webs adapted to be secured between the adjacent bars of either an upright or cross-piece. 30

In testimony whereof I have signed my name to this specification in the presence of two subscribing witnesses.

CHARLES MITCHELL.
